UNITED STATES PATENT OFFICE.

WILLIAM N. WHITELY, OF SPRINGFIELD, OHIO.

GRAIN-BINDING HARVESTER.

SPECIFICATION forming part of Letters Patent No. 703,328, dated June 24, 1902.

Application filed October 29, 1900. Serial No. 34,682. (No model.)

To all whom it may concern:

Be it known that I, WILLIAM N. WHITELY, a citizen of the United States, residing at Springfield, in the county of Clark and State 5 of Ohio, have invented new and useful Improvements in Grain-Binding Harvesters, of which the following is a specification.

My invention relates to improvements in grain-binding harvesting-machines, and especially to butt-adjusting and grain handling 10 and controlling mechanism; and the objects of my improvements are, first, to provide a butt-adjuster and the accessories thereto—that is, to give motion to this mechanism to hold and control the grain in various directions; second, to provide a fork located at the inner end of the cutting apparatus and near 15 the mouth of the elevator to reach out and draw the grain to the cutting apparatus and force the cut grain back to the mouth of the elevator.

The third object of my invention is to provide a grain-lifting mechanism placed at the rear end of the elevator to assist in elevating 20 long grain and a similar mechanism at the rear of the grain-binder deck to lift and draw the grain over and down the deck to the binding mechanism.

I attain these objects by means of the mechanism shown in the accompanying drawings, in which—

Figure 1 is a front elevation of a harvester and binder. Fig. 2 is a plan view of same. Fig. 3 is a plan view of a portion of a grain-binder, showing the butt-adjuster in position for conveying short grain to the grain-binding mechanism. Fig. 4 is a similar view showing the binder moved forward for the purpose of bringing the butt-adjuster close to the binding mechanism to bind the shortest grain. Fig. 5 is a sectional elevation of the conveying-belts, rolls, stripping-roller, and deck, showing the toothed arm member of the butt-adjuster in four extreme positions of its movement. Fig. 6 is an elevation showing the mechanism for driving the toothed arm member of the butt-adjuster, also showing the wing-board, the vibrating swinging link pivotally connecting the rear end of said toothed arm to said wing-board, also showing the adjusting-lever pivotally connected to said wing-board. Fig. 7 is a detail in plan and elevation of the method of driving the third or stripper-conveyer roller. Fig. 8 is a perspective view of the toothed arm, showing its driving-crank, to which the forward end of the toothed arm is pivotally connected, in position, also showing the vibrating swinging link in position, to which the rearward end of the toothed arm is pivotally connected. Fig. 9 is 55 a detail in perspective of the combined tooth and pivotal bearing for the flexible arm. Fig. 10 is a perspective detail of the combined link and adjusting-lever support. Fig. 11 is a perspective detail of the front tooth and crank-piu bearing. Fig. 12 is a sectional elevation of flexible arm and support. Fig. 13 is a detached detail view of same. Figs. 14 and 15 are a plan and elevation of a rigid arm. Fig. 16 is an inverted view of the pressed-steel channel-shaped back or arm of the butt-adjuster which acts to compress the grain to the binder-deck. Figs. 17 and 18 are a plan and elevation of the depressor. Figs. 19 and 20 are plan and elevation of the depressor-support. Fig. 21 is 60 70 an elevation showing the plate attached to the elevator side and the manner of supporting the wing-board and butt-adjuster driving mechanism. Fig. 22 is a plan and elevation of the pivotal frame which supports the wing-board and butt-adjuster driving mechanism. Fig. 23 is a plan and elevation of the driving-gear for same. Fig. 24 is a plan and elevation of the yoke or pivotal support for the upper part of the pivotal frame. Fig. 25 is a 65 detail of the main driving-shaft. Figs. 26, 27, and 28 are modified sections of the wing-board. Fig. 29 is a plan view of the vertically-reciprocating arm member of the butt-adjuster having teeth placed at an angle to 75 the wing-board for the purpose of forcing the grain coming up with the butts bent toward the rear of the deck that they may be delivered straight to the binding mechanism. Fig. 30 is an elevation and diagram of the vertically-reciprocating arm member of the butt-adjuster having teeth showing the path of each tooth throughout its full movement. Fig. 31 is a front elevation showing method 80 of driving reel and relief-fork from elevator-roll. Fig. 32 is a sectional detail showing how reel-post and relief-fork shaft are supported on and in a tubular bearing. Fig. 33 is an elevation showing relief-fork in various 85 90 95 100 positions.

positions and a diagram of its movement. Fig. 34 is an elevation of the supporting-frame for the reel-post, relief-fork, driving-gear, and relief-fork shaft. Fig. 35 is an elevation of the reel-post. Fig. 36 is a detail in section of the sleeve which supports the reel-post and forms a tubular bearing for the relief-fork shaft. Fig. 37 is a sectional view of the reel and relief-fork driving-gear. Fig. 38 is a detail of the reel and relief-fork crank driving-shaft. Fig. 39 is a detail of the relief-fork. Fig. 40 is a detail of the vibrating rod, one end of which is fixed to some stationary part of the harvester, the other to the upper end of the relief-fork arm. Fig. 41 is a detail of the single-piece metallic box which supports the roller-shaft, driving-gears, and one end of the driving-shaft for the reel and relief-fork driving mechanism. Fig. 42 is an elevation showing the grain-lifting mechanism on the rear end of the elevator, also similar mechanism at the rear end of the deck. Fig. 43 is a plan view of same. Fig. 44 is a perspective view, partly in section, of the pivotal frame C'. Fig. 45 is a perspective view, partly in section, of the bevel driving gear-wheel B¹⁴. Fig. 46 is a perspective view of a portion of a grain-binder, showing the vertically-reciprocating arm member of the butt-adjuster having teeth, the wing-board member of the butt-adjuster, the depressor member of the butt-adjuster, and the operation of the vertically-reciprocating toothed arm member on the grain as it is delivered by the elevator-belts, with the butts of the grain retarded by seizing hold of and piercing the butts of the grain from the top, compressing it onto the binder-deck, and forcing it binderward under the depressor and straightening it for binding.

Similar letters of reference indicate like parts in the different views.

To abbreviate the wording of the specification and claims and that the terms used shall always have the same definite and understood meaning, I append the following explanations.

The word "grain" means the stalk, head, and kernel as growing in the field and includes all cereals, as wheat, corn, rye, oats, barley, &c., or crops of all kinds to be harvested.

The word "harvester" here means an implement, as shown in Figs. 1 and 2, which may have a reeling apparatus A in front of the cutters A', the cutters extending across the swath part of the machine and capable of cutting the crops, a divider A² to separate the crops at the outer end of the machine, a horizontal conveyer A³, extending across the swath part of the mechanism. The elevator A⁴ is usually composed of two endless belts A⁵ and A⁶, Fig. 5, and is placed obliquely, with its mouth A⁷ at the inner end of the horizontal conveyer A³ and its delivery end A⁸ extending to the grain-receptacle A⁹, which is between the elevator A⁴ and the binding mechanism A¹⁰. This receptacle I term the "binder-

deck," and it is usually higher at its receiving side than the binder.

What I term the "grain-binder" is a binding mechanism separate from the grain-harvester and is composed of several working parts in a frame, one portion being below the binder-deck and another above, having a band-placing arm, knot-tying and grain-ejecting mechanism to eject the gavels after being bound. This grain-binding apparatus is movable longitudinally with the grain while the machine is in motion to bind the grain centrally, and it is attachable and detachable from the harvester part of the machine and separable therefrom.

The word "butts" in this case means the butts of the straw of the grain, being that portion cut from the part left standing in the field.

The butt-adjuster is composed principally of three coacting members—viz., a vertically-reciprocating arm member having teeth longitudinally and crosswise disposed operating over and above the binder-deck and over the path of the grain in one direction and upon and into the grain in another direction, a pivotal wing-board member located at the extreme butts of the grain to guide and control the butts of the grain when being operated upon by the vertically-reciprocating toothed-arm member, a pivotally-connected grain-depressor located on the opposite side from the wing-board member of the vertically-reciprocating toothed arm member to hold the grain down while being acted upon by the vertically-reciprocating toothed arm member. The adjusting-lever is an adjunct to the butt-adjuster.

Heretofore butt-adjuster mechanisms did not positively move the grain. The parts intended to move it acted only upon it in a loose state, rubbing along it, sometimes with effect, often not. Consequently the work was imperfect, the binder-deck filled up with grain, and the machine clogged, requiring stoppages to clean it out by the operator. This was very objectionable, and the object of my improvements is to remedy these defects by the positive forcible moving of the butt-ends of the grain to the binder mechanism from the elevator. This I do by my improved butt-adjuster, one member, a long wide vertically-reciprocating arm, having a series of teeth on its under side, which extends over a considerable portion of the grain lengthwise and crosswise at the same time and penetrates entirely through the grain from the top, thereby positively controlling the movement of the grain in whatever direction the arm is caused to move, the arm resting upon the grain and compressing it onto the binder-deck. Said arm is held down in this position by a pivotally-connecting link at its rear end to the wing-board, its front end pivotally connected to a vertically

rotary crank to hold the arm down and reciprocate it, thus forcibly and positively

moving the grain from the delivery end of the elevator to the binder mechanism. Said vertically-reciprocating toothed arm is aided in controlling the grain by a long wing-board member at the butts of the grain, extending their whole length from the elevator to the binder. It is also further aided by a grain-depressor member acting on top of the grain distant from the wing-board and extending from the elevator to the binder and placed opposite the wing-board, the vertically-reciprocating toothed arm intermediate between the depressor and the wing-board. This construction has been found extremely useful, overcoming all the difficulties found in the old methods.

Referring to Figs. 1, 2, 3, 4, 5, 6, 21, 29, and 41, to the upper end of the elevator is attached a single-piece metallic box B, which supports the elevator-rolls B' B² B³ and driving-gears B⁴ B⁵. Upon this plate is formed a bearing B⁶, which receives the driving-shaft B⁷, which is provided at its lower end with a gear B⁸ and at its upper end with a gear B¹³. To the front end of the stripping-roller B³ is secured a gear B⁸, which engages with and communicates motion to the gear B⁹, secured to the lower end of the shaft B⁷, said stripping-roller driven at its rearward end by the gear B¹⁰, secured thereon, (sectional Fig. 7,) which engages with the intermediate gear B¹¹, which is driven by the gear B¹² on the end of the upper roller of the lower elevator, which receives its motion from the main driving mechanism. To the upper end of the shaft B⁷ is secured the bevel-pinion B¹³, which drives the bevel gear-wheel B¹⁴, which is provided with a long hub, as shown in Fig. 45, which passes through the hub C of the pivotal frame C' and forms a long bearing for the gear B¹⁴. The crank-shaft C² is fitted within the hub of the driving-gear B¹⁴, said entire crank-shaft being embraced by the hub of the driving-gear B¹⁴, and the hub of said gear-wheel in turn is journaled at C. The purpose of this construction is to bring the several working parts into a much smaller space than could be done were the crank-shaft to have an independent bearing from the hub of the wheel. It is desirable that the vertically-reciprocating toothed arm member C⁶ of the butt-adjuster be operated near to the wing-board member of the butt-adjuster and that the driving-gear for said vertically-reciprocating toothed arm member C⁶ and parts be kept near the wing-board member of the butt-adjuster. Therefore it is desirable that the construction of the crank-shaft C² and the hub of its driving gear-wheel B¹⁴ be so formed that while affording the necessary journal length it will be very compact. Consequently this construction of the journal for the crank-shaft C² is desirable to be the hub of the driving gear-wheel B¹⁴, being fastened upon the crank-shaft C² or to it, it thereby gives motion to said crank and but a small space is occupied by the several parts.

The crank-pin C⁴ of the crank C³ is adapted to fit into and rotate the front tooth C⁵, which is secured to the vertically - reciprocating toothed arm member C⁶ of the butt-adjuster and is provided with a series of teeth which are serrated or saw-tooth shaped. To the rear tooth C⁷, Figs. 8, 9, 12, and 13, is pivoted a flexible arm D and is provided with a pocket D', which supports a spring D². The lower end of the spring D² is held in the pocket D' by the stud or boss D⁴ on the rear tooth C⁷.

The tooth C⁷ and flexible arm D are pivotally secured by a pin D⁵, passing through the upper part of the tooth C⁷ and the hub D₉ of the arm D. The object of providing a flexible arm for the vertically-reciprocating toothed arm member C⁶ of the butt-adjuster is should any large bunches of grain come under same it would yield upwardly and immediately return to its normal position after the removal of the grain.

To the upper end of the flexible arm D is pivoted the vibrating link E, Figs. 8 and 10, and at the lower end link E is pivoted to the combined link and adjusting-lever support E', which is rigidly secured to the side of the wing-board E². (See Fig. 6.)

Working in conjunction with the grain-compressing action of the vertically-reciprocating arm member C⁶ of the butt-adjuster, which is channel-shaped, with teeth on its under side, both longitudinally and crosswise disposed, which pierce or enter the grain at several points from the top in its downward movement and compress the grain to the deck, is the depressor F. (Shown in Figs. 5, 6, 17, and 18.) Figs. 5 and 6 show the depressor F attached to the deck-cover F', which has a portion of its length cut away to leave an opening for the vertically-reciprocating arm member C⁶ of the butt-adjuster, having teeth to operate in its lower arm F², extending downwardly to near the binding mechanism, and as the vertically-reciprocating arm member C⁶ of the butt-adjuster, having teeth, is shown in its four extreme positions it is evident that the butts of the grain are penetrated by the teeth of arm and compressed toward the deck and forcibly drawn under the depressor-arm F² and held there while being conveyed to the binding mechanism. The depressor F is pivotally connected to the elevator portion of the machine by the eye-plate F³, which is provided with an oblong slot F⁴ and also with a slot on the side to receive the depressor member F of the butt-adjuster. By said pivotal connection the depressor member F of the butt-adjuster swings in unison with the wing-board member E² of the butt-adjuster and the vertically-reciprocating arm member C⁶ of the butt-adjuster, having teeth, throughout the various horizontal adjustments of all of said butt-adjuster parts while at work.

The outer end of the depressor F is flexibly connected to the operator's adjusting-lever F⁵ by a clip F⁶, which is rigidly secured to the

operator's lever F^5 and provided with an eye through which the rod F is permitted to move freely longitudinally.

The operator's adjusting-lever F^5 (shown 5 in Figs. 1, 2, 3, 4, 5, and 6) is curved downwardly, the lower end F^7 being pivotally connected to the combined link and adjusting-lever support E' . The other end of the lever F^5 is provided with notches F^9 , adapted to fit 10 into the catch F^8 , secured to the binder-deck cover F' , terminating in a handle in easy reach of the operator.

In Fig. 21, B is the single-piece metallic box, which pivotally supports the wing-board member E^2 of the butt-adjuster and the driving mechanism for the vertically - reciprocating toothed arm member C^6 . The pivotal frame C' is provided at its lower part with a box G and cap G' , Fig. 22. The upper part is provided with lugs $G^2 G^3$, adapted to receive the yoke G^4 . This yoke G^4 (shown in detail in Fig. 24) is made to fit over the projecting boss G^5 , formed on the upper part of the bearing B^6 of the single-piece metallic box B . The 25 single-piece metallic box B being in position, the hub of the bevel gear-wheel B^{14} is placed in the hub C of the pivotal frame C' , the crank C^2 inserted and secured. The yoke G^4 is placed on the projecting boss G^5 of the bearing B^6 . The driving-shaft B^7 , with gear B^9 secured in position, is placed in the bearing B^6 and the pinion B^{13} secured in place at the top. In the single-piece metallic box B is cast an opening G^6 and a bearing G^7 , adapted to receive the box G of the pivotal frame C' , which is provided with a cap G' . The above-named parts being in position on the single-piece metallic box B and the pivotal frame C' , with its bevel gear-wheel B^{14} and crank C^2 secured 40 together, the box G is placed in the opening G^6 and around the bearing G^7 and the cap G' placed in position and secured. The yoke G^4 is then bolted or rigidly attached to the pivotal frame C' , which completes the pivotal construction of the driving mechanism for the vertically-reciprocating toothed arm member C^6 of the butt-adjuster. The shaft B^7 being driven from the stripper- roll and having its axis at a right angle to the crank C^2 on the crank-shaft C^3 , their center lines intersecting and constructed as above stated, it will be evident that the pivotal frame C' , supporting the wing-board member E^2 of the butt-adjuster, the vertically - reciprocating 55 arm member C^6 , having teeth, and its driving mechanism, may be adjusted horizontally to the position required to bind long or short grain and the driving-gears be held in mesh while operating in any of its several positions.

60 The term "horizontally adjusting the butt-adjuster" means to swing it back and forth to and from the band-line of the binder in order that the short or long grain may be brought in proper binding position centrally to the band and by this means not require the too - frequent adjustment of the grain-binder itself, as would otherwise be necessary

in order that the binding might be central to the straw, and as the grain grows very uneven in height from the ground it becomes necessary to make frequent adjustment, and as this butt-adjuster is light and small and very easily moved horizontally it is usually more practical to deliver the grain centrally for binding by this than moving the binder, it being the heavier.

Referring to Figs. 2, 3, 4, Fig. 2 shows the vertically-reciprocating toothed arm member C^6 of the butt-adjuster in its normal position in line with the elevator A^4 for binding long grain, and by means of the operator's adjusting-lever F^5 the wing-board member E^2 , the depressor member F , and vertically-reciprocating toothed arm member C^6 of the butt-adjuster, with its connections to the wing-board, are adjusted horizontally on the deck. Fig. 3 shows the vertically - reciprocating toothed arm member C^6 of the butt-adjuster in position to bind short grain, and in Fig. 4 the binder and deck are moved forward, showing the vertically-reciprocating toothed arm member C^6 of the butt-adjuster in place for binding very short grain.

Figs. 26, 27, 28 show modified sections of the wing-board member E^2 of the butt-adjuster, taken on the line xx in Fig. 30. The wing-board member of the butt-adjuster may be made L-shaped, as in Fig. 26, in which E^3 is the wing-board and H^5 the strip or straight, as shown in Fig. 27, in which E^4 is the wing-board and H^5 the strip; but I prefer to make it as shown in Fig. 28, in which E^2 is the wing-board and H^5 the strip, so that the lower edge may be made to scrape the deck when being adjusted for short grain, the strip H^5 being the same construction in the several modifications of the wing-board. This vertically-reciprocating arm member C^6 of the butt-adjuster, having teeth longitudinally and crosswise disposed, in its operation reaches out and over the grain at the delivery end of the elevator, and as the arm is on the downward path reaching over the grain and into the delivery end of the elevator, piercing the straw at several points about the butt-end of the grain, compressing and forcibly moving the grain from the elevator to the binder. This is very important, as the butts are retarded in passing the cutting apparatus by the action of the horizontal grain-conveyer and the uncut grain acting to retard the butts. Therefore the grain reaches the binder-deck obliquely, heads downward in advance of the butts. Consequently it is necessary to confine the grain on the binder-deck and move the butts faster than the heads are then moving to bind the gavel centrally and have the straws straight. This is one object of my invention, and it must have a positive motion and operate upon the butts of the grain automatically and forcibly. Another object is to positively and forcibly move the grain from the elevator to the binding mechanism under all conditions.

Referring to Figs. 5 to 30, it will be shown how the above is attained. In Fig. 5 are shown the elevator - belts A^5 and A^6 , the mouth A^7 of the elevator, the horizontal conveyor A^8 , which conveys the cut grain to the mouth A^7 of the elevator, where the elevators A^5 and A^6 convey the grain upwardly to the deck, assisted by the third or stripping roller B^3 . The depressor member F being in position, its lower arm F^2 ready to receive the compressed grain, the vertically-reciprocating toothed arm member C^6 , rotating in the direction of the arrow, being over and above the grain at the point marked 1 and in its rotation descends to 2, its many teeth entering or piercing the grain at various points, compressing and forcing the butts down to the deck at the point 3. The butts of the grain will now be under the depressor F^2 and strip H^5 and are confined there during their downward movement to the binding mechanism. Fig. 30 shows a diagram of the path of each tooth and clearly shows how that when the vertically-reciprocating arm member C^6 having teeth, has reached the point 3 it has reached over and into the delivery end of the elevator, penetrated the butts of the grain, and forcibly compressed them to the deck and under the depressor F^2 and strip H^5 and conveys them some distance down the deck before returning to repeat the operation. The vertically-reciprocating arm member of the butt-adjuster having teeth travels fast enough to bring the butts and heads in line before reaching the binding mechanism.

In Fig. 29 is shown the vertically-reciprocating arm member of the butt-adjuster C^6 , having teeth at an angle to the wing-board member E^2 of the butt-adjuster. This is done so that in case the butts of the grain coming from the elevator are bent the operation of the vertically-reciprocating arm member of the butt-adjuster C^6 , having teeth, will be to draw them toward the rear of the binder far enough to be straightened before reaching the binding mechanism, the upward-extending portion D of the vertically-reciprocating toothed arm member of the butt-adjuster C^6 extending outwardly and pivoted to the vibrating link E , the lower end of which is pivotally connected to the wing-board member E^2 of the butt-adjuster outside of the grain. The front tooth C^5 is made wider than teeth C^7 , C^8 , and C^9 to act over a greater area of grain in front near the elevator than in the rear opposite the band-needle for the purpose of moving the grain vigorously near the elevator to clear it, and as the teeth C^7 , C^8 , and C^9 are each narrower than the other act over less area of grain and at the end of their movement lift upwardly out of same to avoid clogging the needle with the grain.

Fig. 31 is a front elevation of the reel and fork driving mechanism. J is the reel-post, its lower end adapted to fit over the bearings J^1 J^2 , through which is passed the tubular bearing J^3 , which forms a pivotal joint and

support for the reel-post J . Passing through the tubular bearing J^3 is the fork crank-shaft J^4 , which supports and is driven by the bevel-wheel J^5 , the end of the crank-shaft J^4 passing through and supported by the bearing J^6 , being a part of the reel and fork supporting frame J^7 .

Fig. 32 is a detail of frame J^7 , showing a part of the bearings and tubular bearing J^3 in section. The end of the shaft J^4 terminates in a crank J^8 , on which is pivoted the fork J^9 . The lower end of the same is provided with a toothed plate J^{10} , and to its upper end is pivotally attached a vibrating rod J^{11} , the other end being secured to the harvester at J^{12} . To the upper part of the elevator side is secured the single-piece metallic box B , which supports the upper elevator-rolls and the gears B^4 and B^5 . On the shaft K is secured the gear K' , which engages the gear K^2 on the shaft K^3 , passing through the bearing K^4 . The end of shaft K^3 is provided with a pinion K^5 , which engages the gear J^5 . (Shown in section in detail, Fig. 37.) To the gear J^5 is secured or cast thereon the sprocket-wheel K^6 , which through the medium of the chain K^7 and reel-driving sprocket K^8 , as shown in Fig. 31, rotates the reel. These several parts being in position, as shown in Fig. 31, the gear J^5 is secured to the shaft J^4 by a pin K^9 , passing through the hub of the gear J^5 and shaft J^4 . Fig. 33 shows the fork J^9 in six positions of its movement and a diagram of the path of the tooth throughout its movement. Fig. 34 shows a front elevation of the supporting-frame J^7 for the reel-post J , relief-fork J^9 , driving-gear J^5 , and shaft J^4 . It will be seen that the fork J^9 reaches upward and outward into the grain and in its return movement bringing the grain in against the cutters and forcing the cut grain backward within reach of the elevators.

Figs. 34, 35, 36, 37, 38, 39, 40 are details of the above parts.

In Fig. 42 is shown a portion of a harvester to which is attached the grain-lifter mechanism. The arm M is provided with a number of teeth, the forward tooth adapted to receive the crank-pin M' , which is formed on the wheel M^2 on the elevator-roll B^2 of the elevating mechanism, the toothed arm M extending downward parallel with the elevator side, the lower side end being bent downward and pivotally connected to the vibrating lever M^3 , the lower end of the lever M^3 being pivoted to some stationary part of the harvester, as at M^4 on the frame in this case. The toothed arm having an orbital reciprocating movement the teeth rise up into the grain, lifting and carrying it upward and forward to assist in elevating long grain.

Figs. 42 43 also show the grain-lifter at the rear of and parallel to the end of the binder-deck. The forward end of the tooth-arm M^5 is provided at its upper end with a tooth adapted to receive the crank-pin M^6 of the crank M^7 , secured to the stripper-roll shaft

M⁸ of the elevator mechanism, the lower end of the same being pivoted to the frame by the vibrating lever M⁹, and by the rotation of the crank M⁷ the toothed arm M⁵ is given 5 an orbital reciprocating movement operating to rise up into the grain which has been elevated to the binder-deck, lift and carry it toward the binding mechanism.

What I claim, and desire to secure by Letters Patent of the United States, is—

1. In a grain-binding harvester, in combination, a horizontal grain-conveying belt, a pair of grain-elevator belts to elevate the grain from the horizontal grain-conveying belt to 15 the binder-deck, a binding mechanism, a binder-deck intermediate between the grain elevator and binding mechanism, a butt-adjuster mechanism, supported on the elevator portion of the machine independent of the 20 binding mechanism, one member thereof having downwardly-projecting longitudinally and crosswise disposed teeth operating over and into the path of the butts of the grain, said member extending downward and stubbleward over the forward end of the binder-deck and having an orbital reciprocal movement faster than the movement of the heads of the grain in approximately the vertical 25 plane of the member, the movement of the member in the lower portion of its orbit being stubbleward and binderward, whereby the butts of the grain are pierced, compressed and carried down the binder-deck toward the binder mechanism faster than the heads.

2. In a grain-binding harvester, in combination, a horizontal grain-conveying belt, a pair of grain-elevator belts, a grain-binding mechanism arranged at the side of the machine and distant from the grain-elevator, a binder-deck intermediate between said grain elevator and binding mechanism for the reception 40 of the cut grain from the elevator, a butt-adjuster mechanism, one member thereof consisting of an arm having downwardly-projecting teeth and located over the forward end of the binder-deck, means for moving said member alternately stubbleward and grainward, said member operating upon the top of the grain near the butts thereof and piercing 45 the grain at different points compressing it downward upon the binder-deck and positively moving it from the elevator to the binding mechanism; said butt-adjuster mechanism pivoted to swing parallel to the plane of 50 the binder-deck that the grain may be bound centrally of its length, be it long or short.

3. In a grain-binding harvester, in combination, a horizontal grain-conveying belt, a pair of grain-elevator belts, a binding mechanism, 60 a binder-deck intermediate between the grain elevator and binding mechanism, a butt-adjuster mechanism connected with and supported upon the elevator portion of the machine independent of said grain-binder, one 65 member of said butt-adjuster consisting of an arm having downwardly-projecting teeth lengthwise and crosswise disposed and located

over the forward end of the binder-deck to pierce the grain downward near the butts and move it binderward, a crank connected to and 70 driving said arm, the shaft of said crank horizontally disposed and extending over and above the path of the butts of the grain, said shaft supported by the elevator-frame portion of the machine and driven by means of gearing secured to the front end of one of the grain-moving roller-shafts; another member of said butt-adjuster mechanism consisting of a grain-depressor pivotally supported and located upon one side of the said toothed arm 75 member of the butt-adjuster, to hold the grain down onto the binder-deck and prevent its rising from its depressed condition where forced by said toothed arm member; said grain-depressor moving in unison with said toothed-arm butt-adjuster member in adjustment over the binder-deck parallel to the plane thereof for the purposes shown and described.

4. In a grain-binding harvester, in combination, a horizontal grain-conveying belt, a pair of grain-elevator belts, a binding mechanism, a binder-deck intermediate between the grain-elevator belts and binding mechanism, a butt-adjuster mechanism composed substantially 95 of three coacting members, each pivotally supported upon the elevator-framework of the machine independent of the grain-binder, one member thereof consisting of a wing-board extending from near the grain-delivery end of the elevator toward the binder mechanism along the path of the butts of the grain; another member thereof consisting of a vertically-reciprocating orbitally-moving arm having downwardly-projecting teeth on its under 105 side and located over the forward end of the binder-deck, means for moving said member alternately stubbleward and grainward, said member operating over and above the path of the butts of the grain in one portion of its orbit, 110 and into and with the grain near the butts in its return movement between the grain-delivery end of the elevator and the binding mechanism, the teeth of said arm piercing the grain downward at different points and compressing it upon the binder-deck and forcibly moving it toward the binder mechanism; another member thereof consisting of a grain-depressor, its upper end pivotally connected to a fixed portion of the machine and extending 115 over the grain binderward, along the side of the teeth of the butt-adjuster arm.

5. In a grain-binding harvester, in combination, a horizontal grain-conveying belt, a pair of grain-elevator belts, a binding mechanism, 125 a binder-deck intermediate between said elevator-belts and binding mechanism, a butt-adjuster mechanism, one member thereof consisting of a vertically-reciprocating arm having downwardly-projecting teeth on its under 130 side and located over the forward end of the binder-deck, means for moving said member alternately stubbleward and grainward to pierce the grain downward at different points

lengthwise near the butts, said arm and its teeth extending over a considerable portion of the grain lengthwise and crosswise to grasp the grain as it comes from the elevator and compress it down upon the binder-deck and positively move it binderward.

6. In a grain-binding harvester, in combination, a horizontal grain-conveying belt, a pair of grain-elevator belts, a binder mechanism, a binder-deck intermediate between the elevator-belts and binding mechanism, a butt-adjuster mechanism, one member thereof consisting of a wing-board at the butts of the grain extending from the elevator to the binding mechanism, another member thereof consisting of a vertically-reciprocating arm having a series of teeth on its under side downwardly projecting and longitudinally and crosswise disposed and located over the forward end of the binder-deck, means for moving said member alternately stubbleward and grainward and extending over a considerable portion of the butts of the grain, the grainward end of said arm having a greater vertical movement than its stubbleward end in moving grainward over the grain; said toothed arm and its teeth compressing the grain down upon the binder-deck and moving it forcibly and positively from the grain-delivery end of the elevator over the binder-deck to the binding mechanism.

7. In a grain-binding harvester, in combination, a horizontal grain-conveying belt, a pair of grain-elevator belts, a binding mechanism, a binder-deck intermediate between the elevator-belts and binding mechanism, a butt-adjuster mechanism, one member thereof consisting of a vertically-reciprocating arm having downwardly-projecting teeth on its under side and located over the forward end of the binder-deck, means for moving said member alternately stubbleward and grainward, said member operating over and above the grain upon the binder-deck in one portion of its orbit and near the butts thereof, the teeth of said arm piercing the grain in its downward movement over the binder-deck at different points; said arm and teeth compressing the grain upon the binder-deck and moving it binderward, said butt-adjuster mechanism and grain-binding mechanism being each separately and independently adjusted in relation to each other for the purposes herein set forth and described.

8. In a grain-binding harvester, in combination, a horizontal grain-conveying belt, a pair of grain-elevator belts, a binding mechanism, a binder-deck between the elevator-belts and binding mechanism, a grain-butt-adjuster mechanism, one member thereof consisting of a wing-board at the butts of the grain and extending from the elevator to the binding mechanism over the binder-deck; another member thereof consisting of a vertically or bitally reciprocating arm having downwardly-projecting teeth on its under side and located over the forward end of the binder-deck, said

member acting over and upon the grain near the butts thereof in one portion of its orbit between the elevator and binding mechanism in conjunction with said wing-board, and connected to and driven from the elevator portion of the machine by a suitable mechanism above and forward of the grain-path and independent of the grain-binder mechanism and binder-deck portions of the machine; said butt-adjuster members pivoted to swing parallel to the plane of the binder-deck to adjust the different lengths of grain centrally to the band.

9. In a grain-binding harvester, in combination, a horizontal grain-conveying belt, a pair of grain-elevator belts, a binding mechanism, a binder-deck intermediate between the elevator-belts and binding mechanism, a butt-adjuster mechanism, one member thereof consisting of a wing-board pivotally connected at its upper end by a suitable mechanism to the forward upper portion of the elevating mechanism in front of the path of the grain and extending over the binder-deck binderward, to swing parallel to the plane of the binder-deck; another member thereof consisting of a vertically-reciprocating arm having downwardly-projecting teeth on its under side and located over the forward end of the binder-deck, a horizontally-disposed cranked shaft to operate said arm, said shaft extending rearward over the path of the grain on the binder-deck and connected by its crank to the grainward end of said toothed arm, a horizontal bearing for said shaft pivotally connected to a part of the elevator-framework to allow the butt-adjuster mechanism to swing parallel to the plane of the binder-deck for the purpose of moving the grain centrally to the binding mechanism whether it be long or short, said cranked shaft having a gear secured thereto at its forward end and gears located on the front of the elevator-framework for driving said crank-shaft.

10. In a grain-binding harvester, in combination, a horizontal grain-conveying belt, a pair of grain-elevator belts, a binding mechanism, a binder-deck intermediate between the elevator and binding mechanism, a binder-deck cover located over the path of the grain from the elevator to the binding mechanism, a butt-adjuster mechanism, one member thereof consisting of a vertically-reciprocating arm having downwardly-projecting teeth and located over the forward end of the binder-deck and connected to the grain-elevator portion of the machine, a crank mounted upon said elevator parts for operating said arm, another member thereof consisting of a grain-depressor alongside of the teeth of the arm butt-adjuster member to depress the grain down upon the binder-deck, said depressor being pivotally connected to a fixed part of the machine at its grainward end over the grain-path and extending over the grain binderward to move parallel to the plane of the binder-deck in unison with said toothed

arm member of the butt-adjuster throughout its movements in adjusting the different lengths of grain central to the binding mechanism.

- 5 11. In a grain-binding harvester, in combination, a horizontal grain-conveying belt, a pair of grain-elevator belts, a binding mechanism, a binder-deck intermediate between the elevator and binding mechanism, a butt-
10 adjuster mechanism, one member thereof consisting of a vertically-reciprocating arm having downwardly-projecting teeth on its under side and located over the forward end of the binder-deck; a rotary crank mounted
15 upon the elevator part of the machine connected to the grainward end of the arm for imparting a vertically, reciprocating, orbital motion to said arm, raising said arm and teeth above the grain and over it when moving in one portion of its orbit and into and compressing the grain in its return movement; said toothed arm member having a channel-shaped compressing portion above the points of its teeth to compress the grain
20 25 downward on the binder-deck, a wing-board member of said butt-adjuster mechanism for the purpose of forcibly moving the grain from the grain-delivery end of the elevator to the binding mechanism under compression and
30 a link connection between the stubbleward end of said arm and the wing-board.

12. In a grain-binding harvester, in combination, an elevating and binding mechanism, a binder-deck intermediate between the elevator and binding mechanism, a butt-adjuster mechanism, one member thereof consisting of an arm having a series of downwardly-projecting teeth on its under side, longitudinally and crosswise disposed thereto and located
35 over the forward end of the binder-deck, a crank connected to the grainward end of said arm, the shaft of said crank horizontally disposed and extending forward of the grain-path, a vibrating link, the upper end of said link pivotally connected to the stubbleward end of said arm, a wing-board member pivotally attached to the elevator portion of the machine and extending binderward along the butts of the grain and pivotally supporting
40 45 50 said link, said crank and vibrating link operating to move the toothed arm member of the butt-adjuster vertically and orbitally over and above the path of the grain in one portion of its orbit toward the elevator and downward into and on the grain compressing it upon the binder-deck, and by the action of said crank forcibly moving the grain binderward in its return movement, a grain-depressor member of said butt-adjuster located
55 60 65 upon one side of said toothed arm member, its grainward end pivotally connected to a fixed portion of the machine, its stubbleward end extending binderward to hold the grain onto the binder-deck.

- 65 13. In a grain-binding harvester, in combination, an elevating and binding mechanism, a binder-deck intermediate between the ele-

vator and binding mechanism, a butt-adjuster mechanism located at the forward end of the machine between the elevator and binding mechanism, one of its members consisting of a wing-board pivotally connected to the elevator portion of the machine above the binder-deck and entirely independent of the binder adjustments, a vertically-inclined vibrating link pivotally connected at its lower end to said wing-board, a toothed arm member of the butt-adjuster having an upwardly-extending portion pivotally connected to the upper end of said link, said toothed arm member having downwardly-projecting teeth and located over the forward end of the binder-deck and operating over the grain near the butts in one portion of its orbit and into the grain to draw it down to the binder in its return movement; said vibrating link controlling all of the movements of the stubbleward end of said toothed arm member, a horizontal cranked shaft journaled over the path of the butts of the grain and supported upon the elevator portion of the machine and controlling all of the movements of the grainward end of said toothed arm.

14. In a grain-binding harvester, in combination, an elevating and binding mechanism, a binder-deck intermediate between the elevator and binding mechanism, a butt-adjuster mechanism, one member thereof consisting of a vertically-reciprocating orbitally-moving toothed arm mechanism, said arm member having a series of downwardly-projecting teeth in the line of its length and crosswise thereto and located over the forward end of the binder-deck, means for moving said member alternately stubbleward and grainward, said member operating over and above the path of the grain and near the butts thereof in one portion of its orbit, a binder-deck cover terminating at its forward edge rearward of the forward edge of the binder-deck, the grainward end of said toothed arm intermittently occupying the open unobstructed space for its free action forward of the binder-deck cover rearward of the butt-line of the grain between the elevator and binding mechanism, the grainward end of said arm moving above the top-most point of the elevator grain-delivery and in close proximity thereto, to grasp the highest flow of the grain as it comes from the elevator and force it downwardly to the binder-deck and compress it thereon, and forcibly moving said grain over the binder-deck binderward.

15. In a grain-binding harvester, in combination, a cutting apparatus, a horizontal grain-conveying belt, a pair of grain-elevator belts between which the grain is seized and moved, two upper rollers for said grain-belts, a stripping-roller in near proximity thereto, a binding mechanism, a binder-deck intermediate between the stripping-roller and grain-binding mechanism, a butt-adjuster mechanism working in coöperation with said elevating mechanism and stripping-roller, one mem-

ber thereof consisting of a vertically-reciprocating arm having downwardly-projecting teeth and located over the forward end of the binder-deck, a crank connected to and operating said arm, the shaft of said crank horizontally disposed and extending over and above the path of the butts of the grain, said shaft driven from one of said roller-shafts, said rollers and reciprocating arm operating to move the grain binderward, a single-piece metallic combination-box secured to the forward upper end of the elevator portion of the machine forming a support for the forward ends of the upper roller-shafts of the upper and lower elevators and stripping-roller shaft, holding the same in working contact with each other and supporting said horizontally-disposed crank-shaft, a driving-gear mechanism for said arm member located on said combination-box and connecting to the forward end of said stripping-roller shaft, a wing-board pivotally connected to the elevator portion of the machine independent of the binding mechanism and extending over the binder-deck binderward along the path of the butts of the grain.

16. In a grain-binding harvester, in combination, an elevating and binding mechanism, a binder-deck intermediate between the elevator and binding mechanism, a butt-adjuster mechanism, one member thereof consisting of a vertically-reciprocating arm having downwardly-projecting teeth and located over the forward end of the binder-deck, means for moving said member alternately stubbleward and grainward, said member operating over and in the grain near the butts thereof between the elevator and grain-binder, a vibrating link, the upper end of said link pivotally connected to the stubbleward end of said toothed arm member to guide its movements, a wing-board member pivotally connected to the elevator portion of the machine and extending along the butts of the grain over the binder-deck, and pivotally supporting said vibrating link near its stubbleward end, a crank pivotally connected to the grainward end of said arm, the shaft of said crank horizontally disposed and extending over and above the path of the butts of the grain to cause said toothed arm to rise above the grain in one portion of its orbit and descend into the grain upon the binder-deck and compress said grain upon the binder-deck in its return toward the binder, a driving mechanism for said crank secured to the forward end of one of the grain-moving roller-shafts.

17. In a grain-binding harvester, in combination, an elevating and binding mechanism, a binder-deck intermediate between the elevator and binding mechanism, a butt-adjuster mechanism, one of its members consisting of a vertically-reciprocating arm having downwardly-projecting teeth and located over the forward end of the binder-deck, a rotary crank for operating said arm pivotally con-

nected to the grainward end of said arm below the main portion near the ends of the teeth, the crank-axle being journaled low horizontally upon the elevator portion of the machine, said pivotal connection being below the arm to avoid height of the parts directly concerned.

18. In a grain-binding harvester, in combination, an elevating and binding mechanism, a binder-deck intermediate between the elevator and binding mechanism, a butt-adjuster mechanism, a rotary crank, the shaft of said crank horizontally disposed and supported by the elevator-frame portion of the machine for said butt-adjuster, a gear-wheel journaled upon the elevator portion of the machine driving the shaft of said crank, the hub of said gear-wheel embracing said entire shaft of said crank and rigidly attached thereto forming a journal outside of the cranked shaft for the purpose of economizing space and using smaller parts.

19. In a grain-binding harvester, in combination, an elevating and binding mechanism, a binder-deck intermediate between the elevator and binding mechanism, a butt-adjuster mechanism, one member thereof consisting of a wing-board pivotally connected to the elevator portion of the machine and extending binderward over the binder-deck, another member thereof consisting of a vertically-reciprocating arm having downwardly-projecting teeth and located over the forward end of the binder-deck, a driving-crank for operating said arm, a cranked shaft for said crank and gearing for driving the same; a pivotal frame C, forming a journal-bearing for said cranked shaft, a single-piece metallic box B of the elevator-framework to which said frame C is pivoted to allow said butt-adjuster members to swing parallel to the plane of the binder-deck and to sustain the same in their proper working relations to each other and to the binder-deck throughout the adjustments of said butt-adjuster members.

20. In a grain-binding harvester, in combination, a horizontal grain-conveying belt, an elevator, a grain-binder, a binder-deck intermediate between the elevator and grain-binder, a butt-adjuster mechanism, one member thereof consisting of a wing-board, its grainward end pivotally connected to the elevator near the elevator-belts, said wing-board extending along and guiding the butts of the grain to the binder, a vibrating link pivotally supported by said wing-board member, a vertically-reciprocating arm member having downwardly-projecting teeth and located over the forward end of the binder-deck, its stubbleward end pivotally supported by said vibrating link, a crank-driving mechanism for operating said arm, a bearing pivoted to the elevator-frame in which the shaft of said crank is horizontally journaled, an adjusting-rod, its forward end pivotally connected to said wing-board member and having notches in its rear end, a catch located on

the binder-deck cover to engage with the notches on the rearward end of said adjusting-rod for the purpose of adjusting and positively locking said butt-adjuster mechanism 5 in different positions for the purposes herein set forth and described.

21. In a grain-binding harvester, in combination, an elevating and binding mechanism, a binder-deck intermediate between the elevator and binding mechanism, a butt-adjuster mechanism, one member thereof consisting of a wing-board pivotally connected to the elevator part of the machine near the elevator-belts, another member thereof consisting of 15 a vertically-reciprocating orbitally-moving arm having downwardly-projecting teeth longitudinally and crosswise disposed and located over the forward end of the binder-deck, a pivotal swinging-link connection between 20 the stubbleward end of said arm and the wing-board to guide said arm in its adjustment over the binder-deck parallel to the plane thereof; a driving-crank pivotally connected to the grainward end of said arm to operate 25 said arm, the cranked shaft of said crank horizontally journaled in a connecting-frame to the grainward end of said wing-board member, another member thereof consisting of a grain-depressor pivotally connected to a fixed 30 part of the machine under which the grain is forced by said toothed arm member; an adjusting-rod connecting to one or more of said members and extending within reach of the operator, and held in adjustment by a 35 connection to a fixed part of the machine controlling all of said members in their adjustments while working in unison with each other.

22. In a grain-binding harvester, in combination, an elevating and binding mechanism, a binder-deck intermediate the elevating and binding mechanism, a butt-adjuster mechanism, an inclined shaft by which its principal members are pivotally connected to the elevating part of the machine and by means of which said members have adjustment over the binder-deck parallel to the plane thereof, a gear connection for operating one of the members of said butt-adjusting mechanism, 45 50 said gear connection located on the elevating part of the machine and one member thereof being mounted on the upper end of and driven by said inclined shaft to allow said butt-adjuster to swing parallel to the plane 55 of the binder-deck, a yoke-bracket G⁴ pivotally surrounding the bearing of said inclined driving-shaft and holding said gear connection in engagement, a forwardly and rearwardly extending crank-shaft, the other member 60 65 of said gear connection located on the forward end of said crank-shaft, a driving mechanism from one of the grain-moving rollers for said inclined driving-shaft, one member of the butt-adjuster consisting of 65 a pivotal portion connected to said yoke-bracket, another member consisting of a toothed arm driven by said crank-shaft, said

driving crank-shaft rotatably supported at its forward end by said pivoted member.

23. In a grain-binding harvester, in combination, an elevating and binding mechanism, a binder-deck intermediate between the elevating and binding mechanism, a butt-adjuster mechanism, an inclined pivot located outside the path of the grain and connected 70 with the elevator part of the machine upon which two members of the butt-adjuster are arranged to swing together parallel to the plane of the binder-deck, one member consisting of a wing-board, and one of a vertically-reciprocating arm member having downwardly-projecting teeth and located over the forward end of the binder-deck, a driving-crank pivotally connected to the grainward 75 end of said arm, a shaft for said crank horizontally disposed and extending over and above the path of the butts of the grain on the binder-deck, said crank and shaft mounted 80 on said wing-board.

24. In a grain-binding harvester, in combination, an elevator and binding mechanism, a binder-deck between the elevator and binding mechanism over which the grain passes to the binding mechanism, a butt-adjuster mechanism, one member thereof consisting of 90 a wing-board at the butts of the grain extending from the elevator over the binder-deck toward the binding mechanism to control the butts of the grain endwise in their downward passage to the binding mechanism, another 95 member thereof consisting of a vertically-reciprocating arm having a series of downwardly-projecting teeth both lengthwise and crosswise disposed and located over the forward end of the binder-deck, a crank pivotally 100 connected to the grainward end of said arm to operate same, an upright vibrating link, the upper end of said link pivotally connected to the stubbleward end of said arm, the lower end of said vibrating link pivotally connected to 105 said wing-board member; said butt-adjuster toothed arm member having an orbital movement over and above the grain in one portion of its orbit near the butts and into and with the grain in its return movement, 110 the grainward toothed end of said butt-adjuster arm rising to a higher altitude than its stubbleward toothed part in moving grainward over the grain to embrace it and bring 115 it down to and over the binder-deck toward 120 the binder mechanism.

25. In a grain-binding harvester, in combination, an elevator mechanism, a binder-deck to one side of said elevator, a grain-binding mechanism located stubbleward of said 125 binder-deck, a stripping-roller located between the elevator and binder-deck to lift the grain from the upper end of the lower elevator-belt onto the binder-deck, a butt-adjuster mechanism composed of the following 130 members: a wing-board member extending from the elevator along the path of the butts of the grain over the binder-deck toward the binding mechanism, a vertically-reciprocating

- ing arm member having downwardly-projecting teeth and located over the forward end of the binder-deck, a crank driven from one of the grain-moving rollers and pivotally connected to the grainward end of said arm, a vibrating link the lower end of said link pivotally connected to said wing-board member, the upper end of said link pivotally connected to the stubbleward end of said arm, said toothed arm member of the butt-adjuster having a grainward upward movement by said crank over the grain in one portion of its orbit and down into the grain to move said grain binderward in its return movement; the movement of said toothed arm member of said butt-adjuster being orbital, its grainward portion rising higher above the grain on the binder-deck than its stubbleward non-toothed portion to grasp and gather the up-flowing grain from the elevator and to sweep said grain downward, said arm and teeth acting to compress the grain and compact it on the binder-deck and forcibly moving it binderward, as shown and described.
26. In a grain-binding harvester, in combination, an elevator and binding mechanism, a binder-deck intermediate between the elevator and binding mechanism, a butt-adjuster mechanism, one of its members consisting of a channel-shaped arm having downwardly-projecting teeth upon its under channel side and located over the forward end of the binder-deck, means for moving said member alternately downward stubbleward, upward and grainward, that the edges of said channel may engage with the grain and aid in compressing and holding it down to the binder-deck in conjunction with the teeth while being moved binderward.
27. In a grain-binding harvester, in combination, a grain elevator and binding mechanism, a binder-deck intermediate between the elevator and binding mechanism, a butt-adjuster mechanism, one member thereof consisting of a flexibly-divided toothed arm to yield upwardly to compress large or small quantities of grain, said teeth operating on top of the grain near the butts between the elevator and binding mechanism and located over the forward end of the binder-deck, means for moving said member in an orbit downward, stubbleward, upward and grainward, to rise above the grain in one portion of its orbit and down onto and into the grain in its return motion compressing and moving the grain binderward.
28. In a grain-binding harvester, in combination, an elevator and binding mechanism, a binder-deck, intermediate between the elevator and binding mechanism, a butt-adjuster mechanism, one member thereof consisting of an arm having downwardly-projecting teeth on its under side and located over the forward end of the binder-deck, means for moving said member orbitally over and above the grain in one portion of its orbit and into and with the grain in its return motion, said toothed arm member being composed of two parts pivotally connected together and elastically controlled for the purpose of adaptation to the varying quantities of grain to be acted upon.
29. In a grain-binding harvester, in combination, an elevator and binding mechanism, a binder-deck intermediate between the elevator and binding mechanism, a butt-adjuster mechanism, one member thereof consisting of an arm having downwardly-projecting teeth and located over the forward end of the binder-deck, means for moving said member alternately downward, stubbleward, upward and grainward, said member acting on top of the grain near the butts and over and above the grain in one portion of its orbit and into and with the grain in its return motion, another member of said butt-adjuster mechanism consisting of a wing-board pivotally connected to the elevator portion of the machine at its grainward end, a vibrating link, the upper end of said link rising above the flow of the grain and connected to and supporting the stubbleward end of said arm, the lower end of said link pivotally connected to said wing-board near its lower edge.
30. In a grain-binding harvester, in combination, an elevator and binding mechanism, a binder-deck intermediate between the elevator and binding mechanism, a butt-adjuster mechanism adjustably and pivotally connected to the upper part of the elevator, one member thereof consisting of an arm having downwardly-projecting teeth and located over the forward end of the binder-deck, means for moving said member alternately downward, stubbleward, upward and grainward, the orbit of the grainward end of said arm member having a point higher above the butts of the grain than the orbit of its stubbleward end, the teeth on the stubbleward end of said arm approaching nearer to the wing-board member at the butts to move the butt portion of the grain only so that the last movement of the stubbleward end of said toothed arm will act to turn the butts of the grain and force them around downward to the binding mechanism, straighten the stalks lengthwise to make a straight, square-butted gavel.
31. In a grain-binding harvester, in combination, an elevator and binding mechanism, a binder-deck intermediate between the elevator and binding mechanism, a butt-adjuster mechanism located and operating between the elevator and grain-binding mechanism, one member thereof consisting of an orbitally vertically reciprocating arm having downwardly-projecting teeth and located over the forward end of the binder-deck, means for moving said member alternately stubbleward and grainward, said member moving over and above the grain near the butts thereof in one portion of its orbit and into and on the grain in its return movement, the grainward end of said toothed arm wider than its stubbleward end to act over a greater area of grain at its

grainward end near the elevator than at its stubbleward end for the purpose of moving a large mass of the grain from the elevator downward at each stroke to clear it, and its 5 stubbleward end acting upon a smaller amount of grain to not clog the needle by the grain being pressed hard against it.

32. In a grain-binding harvester, in combination, a pair of grain-elevating belts, a grain-binding mechanism, a binder-deck intermediate between the elevator-belts and binding mechanism, a butt-adjuster mechanism, one member thereof consisting of a swinging wing-board at the butts of the grain, an inclined 15 shaft pivotally connecting said board to the elevator part of the machine, another member thereof consisting of a vertically-reciprocating arm swinging with the wing-board and having a series of teeth downwardly projecting 20 on its under side and located over the forward end of the binder-deck and extending over a considerable portion of the grain on the binder-deck at the butt-ends thereof, a pivotally-swinging link, the upper end of said 25 link pivotally connected to the stubbleward end of said arm, the lower end of said link pivotally connected to and supported by said wing-board, a crank connected to and driving said arm, the shaft of said crank horizontally 30 disposed and overhanging the path of the butts of the grain, a driving-gear located on the forward end of the shaft of said crank and connecting with one of the grain-moving 35 roller-shafts, an adjusting-bar pivotally connected to said wing-board, a U-shaped grain-depressor, pivotally connected to a fixed portion of the machine, the top portion of said 40 depressor pivotally connected to said adjusting-bar and caused by means of said pivotal connections to swing parallel to the plane of the binder-deck in unison with the wing-board member and reciprocating toothed arm member throughout the various adjustments 45 of all of said butt-adjuster parts.

45 33. In a grain-binding harvester, in combination, a pair of grain-elevator belts, a grain-binding mechanism, a binder-deck intermediate between the elevator and binding mechanism on which the grain is received from the 50 elevator, a butt-adjuster mechanism, one member thereof consisting of a swinging wing-board pivotally connected to the elevator part of the machine, and extending from the elevator along the path of the butts of the grain 55 over the binder-deck to the binding mechanism, another member thereof consisting of a vertically-reciprocating arm having downwardly-projecting teeth and located over the forward end of the binder-deck, a vibrating 60 swinging link, the upper end of said link pivotally connected to the stubbleward end of said arm, the lower end of said link pivotally connected to and supported by said wing-board, a crank connected to and driving said 65 arm, the shaft of said crank horizontally disposed, a pivotal frame C' pivotally connected

to the elevator portion of the machine forming a bearing for said horizontally-disposed crank-shaft and pivotally supporting said wing-board member, a vertically-inclined 70 shaft for driving said crank-shaft and forming the pivot for the frame C', a single-piece metallic box B on the front top end of the elevator having a journal-support for said vertically-inclined shaft, said shaft driven from a grain-moving roller-shaft by a gear connection, an adjusting-bar having notches in its rear end and pivotally connected to the wing-board member and extending toward the operator's seat, a catch located on and secured to the 80 binder-deck cover to engage the notches on the rearward end of said adjusting-lever, all of said butt-adjuster parts coacting in their operation in all positions of adjustment for the purposes shown and described. 85

34. In a grain-binding harvester, in combination, an elevator and binding mechanism, a binder-deck intermediate between the elevator and binding mechanism, a butt-adjuster mechanism located and operating between the 90 elevator and binder over the binder-deck to adjust the grain centrally to the binder mechanism; one member thereof consisting of a vertically-reciprocating arm having downwardly-projecting teeth and located over the 95 forward end of the binder-deck, a crank connected to and driving said arm, the shaft or axle of said crank horizontally disposed across the path of the travel of the grain over the binder-deck, a vertically-inclined shaft in 100 front of the grain-path pivotally supported by the elevator portion of the machine to drive said crank-shaft, a pivotal frame pivotally connected to the elevator part of the machine to support said crank-shaft, a wing- 105 board pivotally connected to the elevator portion of the machine and extending along the butts of the grain over the binder-deck binderward, a grain-moving roller pivotally supported by the elevator portion of the machine 110 to drive said butt-adjuster mechanism, said shafts geared together to effect continuous motion to said toothed-arm butt-adjuster mechanism through all of its adjustments parallel to the plane of the binder-deck; said 115 vertically-inclined driving-shaft being the axial pivot on which the toothed arm member and wing-board portion of the butt-adjuster swing. 120

35. In a grain-binding harvester, in combination, a cutting apparatus, a horizontal grain-conveying belt, an elevator and binding mechanism, an orbitally-reciprocating grain-butt-moving arm located at the inner end of the cutting apparatus and meeting 125 ends of the horizontal grain-conveying belt and lower end of the two grain-elevator belts, a rotary crank connected to and driving said arm, the shaft of said crank horizontally disposed, a swinging link to control the movements of said butt-moving mechanism, the 130 forward end of said link pivotally connected

to the upper end of said arm, the rearward end of said link pivotally connected to a portion of the harvester-framing, and an oscillating reel-support having pivotal joints forming 5 a bearing for the crank-shaft operating said arm.

36. In a grain-binding harvester, in combination, a grain cutting and elevating mechanism, an orbitally-reciprocating butt-moving arm located at the inner end of the cutting apparatus and meeting ends of the horizontal grain-conveying belt and elevator-belts, a crank connected to and operating said arm, the shaft of said crank horizontally disposed, a swinging link to control the movements of said butt-moving arm, the forward end of said link pivotally connected with the upper end of said grain-butt-moving arm, the rearward end of said link pivotally connected 15 to a portion of the harvester-framing, and an oscillating reel-support having pivotal joints forming a bearing for the crank-shaft operating said crank and butt-moving arm, and a tubular bearing for said crank-shaft passing 20 through and supported by said pivotal joints.

37. In a grain-binding harvester, in combination, a grain-cutting and grain-elevating mechanism, an orbitally-reciprocating grain-butt-moving arm located at the inner end of the cutting apparatus and meeting ends of the horizontal grain-conveying belt and elevator-belts, a crank for operating said butt-moving arm, the shaft of said crank horizontally disposed, a swinging link to control the 30 movements of said butt-moving arm, the forward end of said link pivotally connected to the upper end of said grain-butt-moving arm, the rearward end of said link pivotally connected to a portion of the harvester-framing, 35 and an oscillating reel-support having pivotal joints and forming a bearing for said crank-shaft, a tubular sleeve-bearing for said crank-shaft passing through said pivotal joints, said crank-shaft in its tubular-bearing pivot having a toothed gear and a chain-wheel mounted thereon and connected thereto, a reel-support consisting of said crank-shaft and its tubular sleeve-bearing supported by 40 said pivotal joints, said chain-wheel operating the reel mechanism and the toothed gear-

ing giving motion to both the fork crank-shaft and reel-chain mechanism.

38. In a grain-binding harvester, in combination, a grain cutting and elevating mechanism, an orbitally-reciprocating grain-butt-moving arm located at the inner end of the cutting apparatus and meeting ends of the horizontal grain-conveying belt and elevator-belts, a crank connected to and operating said butt-moving arm, the shaft of said crank horizontally disposed, a swinging link to control the movements of said butt-moving arm, the forward end of said link pivotally connected to the upper end of said grain-butt-moving arm, the rearward end of said link pivotally connected 55 to a portion of the harvester-framing, an oscillating reel-support having pivotal joints and a tubular sleeve-bearing for said crank-shaft, the center of said crank-shaft and its tubular sleeve-bearing and the 60 oscillating reel-support and the base supporting said reel on the harvester part of the machine being coincident, said crank-shaft receiving its motion from the stubble side of the harvester which also communicates motion to the reel from the same fixed source 65 of power-supply.

39. In a grain-binding harvester, in combination, a binding mechanism, a pair of grain-elevator belts, their rear sides wholly disconnected from each other and terminating in an open unobstructed space for the passage of grain longer than the width of said belts, a binder-deck between the elevator-belts and binding mechanism upon which the grain 80 falls from the elevator, an orbitally-moving vertically-reciprocating grain-lifting toothed arm member at the rearward side of the grain-elevator belts and binder-deck, a driving-chain located at the rear of said elevator to 85 impart motion to said toothed arm and also to the elevator mechanism substantially as specified.

In testimony whereof I have signed my name to this specification in the presence of 95 two subscribing witnesses.

WILLIAM N. WHITELY.
